UNITED STATES PATENT OFFICE

166,062

PACKAGE FOR JEWELRY FINDINGS AND THE LIKE

Murray L. Berrie, New York, N. Y.

Application April 6, 1951, Serial No. 14,740

Term of patent 14 years

(Cl. D58—2)

To all whom it may concern:

Be it known that I, Murray L. Berrie, a citizen of the United States of America, residing at New York city, in the county of New York and State of New York, have invented a new, original, and ornamental Design for a Package for Jewelry Findings and the Like, of which the following is a specification, reference being had to the accompanying drawing, forming part thereof.

In the drawing

Fig. 1 is a plan or top view of a package for jewelry findings, showing my new design;

Fig. 2 is a side view thereof, and

Fig. 3 is an elevational view showing the package in open position.

The lines in Fig. 1 are intended to represent contrast in color.

I claim:

The ornamental design for a package for jewelry findings and the like, substantially as shown and described.

MURRAY L. BERRIE.
